UNITED STATES PATENT OFFICE.

JOSEPH PERCY REMINGTON, OF PHILADELPHIA, PENNSYLVANIA, ASSIGNOR TO REMINGTON MANUFACTURING COMPANY, OF PHILADELPHIA, PENNSYLVANIA, A CORPORATION OF PENNSYLVANIA.

LIQUID-FUEL-FEED SYSTEM.

Application filed October 17, 1921, Serial No. 508,076. Renewed September 24, 1927.

My invention relates to fuel feed or supply systems, my main object being to provide an adequate flow of fuel under practically any and all operating conditions, without excess at any time. I aim to avoid various drawbacks of fuel supply systems heretofore used — such as the loss of fuel while an automobile is standing to which gravity systems are liable, through leakage at the carburetor needle valve; the failure of vacuum systems to furnish sufficient fuel at the very times when adequate supply is most imperative, when running at high speed and in hill climbing; and difficulty with the fuel supply owing to slight leakage of air from the system, as in tank pressure systems. While I prefer to feed the fuel under pressure, I am able to accomplish this without the necessity of maintaining pressure in the supply tank.

Other objects and attendant advantages of my invention will become readily apparent from the detailed description which follows:

In the drawings, Fig. I is a more or less diagrammatic illustration of an automobile fuel feeding system conventionally embodying my invention.

Fig. II is a longitudinal sectional view of a device for feeding the fuel from the supply tank to the carburetor and controlling the flow of fuel.

Fig. III is a horizontal section of the pump taken as indicated by the line III—III in Fig. II.

In the fuel feeding system illustrated in Fig. I, the fuel storage or supply tank is conventionally represented at 1, and the carburetor at 2. Between the tank 1 and the carburetor 2, interposed in the pipe conduit comprising the sections 3 and 4, is a device 5 for feeding fuel and controlling its flow. This device 5 is connected by a pipe 6 with means capable of producing alternate impulses of rarification and compression of the air in said pipe, here shown as an impeller or pulsator 7. This impeller or pulsator 7 comprises a cylinder 8 and a reciprocating piston 9 which may be actuated by any appropriate means, preferably the cam shaft of the motor to which fuel is to be supplied. As described hereinafter, the pul-

sator 7 and the device 5 cooperate as a pump in feeding the fuel under pressure, and the device 5 may also include means for regulating its pressure and flow.

By reference to the larger illustrations, Figs. II and III of the drawings, it will be seen that the device 5 comprises two upright, cylindrical chambers 10 and 11, the former of which I will term a pump chamber, and the latter a pressure chamber, for reasons which will presently become manifest. These chambers 10, 11 are formed by cavities or cups 12 and 13 in a common base member 14 and removable caps or domes 15 and 16 screwed into enlarged brim flanges 17 and 18 of said cup cavities. The dome 15 has a screw threaded axial extension or nipple 19 for attachment of the coupling 20 of the pipe 6 to the impeller or pulsator 7. The cup 12 of the chamber 10 is similarly provided with an axial extension or nipple 21 for the attachment of the pipe conduit section 3 from the fuel supply tank 1. Central stand pipe 22 in the chamber 10 (forming, in effect, an inward extension of the pipe line 3) serves as a means of trapping a portion of the fuel drawn into said chamber during the suction strokes of the impeller or pulsator 7, as hereinafter explained. The displacement of the impeller or pulsator 7 is, in practice, made such that sufficient fuel is drawn from the tank 1 at each suction stroke to substantially fill 85 the pipe line 3 and the chamber 10. Near its top, the stand pipe 22 is pierced with a series of apertures 23 for the passage of the fuel. The pipe 22 is almost wholly surrounded by a filtering screen 25 consisting of a cylinder of fine wire gauze, which at its bottom, is held concentrically spaced about the pipe 22 by an attached ferrule 26, and at its top by a cap piece 27 which closes the top of said pipe 25. The cap piece 27, 90 it will be perceived, extends to a point below the level of the apertures 23, so that the stream of incoming fuel is directed downwardly and prevented from splashing upward into the pipe 6 leading to the impeller 100 or pulsator 7. Upon removal of the dome 15, the filtering screen 25 may be readily withdrawn for cleaning when necessary.

The cups 12 and 13 of the base member

14 are joined by a web 29, and communicate through a duct 30 in said web. This duct 30 terminates in a seat 31 afforded by a protuberance 32 in one side of the cup 13. The 5 flow of the fuel through the duct 30 and into the pressure chamber 11 is automatically controlled by a gravity check or flapper valve 33, which cooperates with the seat 31 and is guided for limited free movement by headed 10 screw studs 34, 34. At one side, cup 13 of the chamber 11 has a depending extension or nipple 35 which serves for the attachment of the coupling 36 of the pipe conduit section 4 leading to the carbureter 2. In order 15 that the pump device 5 may be readily secured to the dash board or other fixture of the automobile, the base member 14 is provided with integral extensions or wings 37-37 which are appropriately slotted as 20 at 38-38 for screws or any other convenient securing means.

The operation is as follows:

During the first suction stroke of the pump impeller or pulsator 7, fuel is drawn 25 from the supply tank 1 through the constantly open conduit 3 and into the chamber 10. During the succeeding pressure stroke, fuel that has been drawn in by the suction is forced through the duct 30, past the valve 33, into the chamber 11, whence it flows to the carbureter 2. If the carbureter 2 is entirely empty at starting, a few strokes may be required to expel air from the system through the carbureter, and to fill or 30 charge the system (particularly the carbureter) with fuel. Upon closure of the needle valve controlling fuel admission to the carbureter 2 (by the accumulation of fuel in the carbureter), the succeeding pressure stroke or strokes of the pulsator 7 can still pass fuel through the check-valve 33 into the chamber 11 and accumulate it there; but this can go on only until the resulting 35 pressure of the air entrapped and confined 40 in the dome 16 substantially balances the pressure impulses from the pulsator. Accordingly, the building up of pressure in the system is limited by the fact that flow of fuel via the pipe 22 is absolutely free 45 and unrestricted, so that fuel (and even air) from above the stand-pipe apertures 23 can always return through the supply conduit 3 to the tank 1, relieving any excess pressure 50 due to the pulsator 7. In practice, the pressure maintained in the chamber 11 depends 55 on the displacement of the impeller or pulsator 7; and I prefer to so proportion this that a substantially constant pressure in the neighborhood of two pounds is maintained 60 in said chamber.

As soon as the carbureter needle valve opens again, even slightly, fuel will flow from the chamber 11 into the carbureter 2 under the accumulated air pressure in said 65 chamber 11. The next pressure stroke of the

pulsator 7 will then force fuel from the pump chamber 10 into the pressure chamber 11, and thence (if the needle valve still remains open) into the carbureter 2; while during the succeeding suction stroke, fuel drawn 70 from the tank 1 will replace what has been injected into the carbureter. Such action will continue and recur so long as and whenever the carbureter needle valve is open.

From this it will be seen that while fuel 75 is surged to and fro (or at least inward) in the supply conduit comprising the pipe line 3 and the pump chamber 10 at every double stroke (suction and pressure) of the pulsator 7, yet it is only as and when permitted 80 by the carbureter regulation that the pressure impulses unseat the check-valve 33 and feed fuel through the delivery connection including the passage 30 and the chamber 11: i. e., only when the outflow from the carbureter under the demand for fuel (as represented by opening of the carbureter 85 needle valve) reduces the back-pressure in the chamber 11 that is maintained by the needle valve when closed. When the carbureter 2 is full, the pump automatically ceases to be operative, except for idle surging of fuel; when the carbureter is taking fuel, the pump becomes operative, and the surging ceases to be "idle", only to the extent of the demand. Any excess of the charge 90 drawn into the chamber 10 on one suction stroke over the current requirements is always permitted to return through the supply line 3 on the succeeding pressure stroke.

It will be seen, therefore, that by reason of the absence of the usual check-valve or the like from the supply line 3, it is practicable to use an impeller or pulsator of sufficient displacement to feed a quantity of fuel exceeding any possible requirements, without incurring any substantial variation in the pressure under which the fuel is fed.

This delivery of fuel even with the conduit open toward the supply, without any 105 check against return of excess fuel, is made possible by energetic inward surging of the fuel under rapid alternations of suction and pressure, such as results from actuation of the pulsator 7 from an automobile engine as 110 described above. For when the pulsator 7 reverses at the end of a suction stroke and begins to exert pressure on the fuel through the elastic fluid cushion in the pipe 6, etc., the inertia of the body of liquid in the supply line 3 serves as a check-valve to allow the pressure to force the liquid out through the check-valve 33 in the delivery (if conditions in the chamber 11 permit),—by virtue 115 of the energy of the inward surge of fuel induced by the preceding suction stroke, as well as of the energy due to the succeeding pressure impulse. And since these effects increase in an ever-increasing proportion with the speed of the engine and the frequency 120 125 130

- of suction and pressure alternations, it follows that as the demand for fuel increases, the effective capacity of the system is augmented still more rapidly. Thus sufficient fuel can be fed to meet the requirements at the carbureter 2 under any and all conditions,—whether the engine be idling at approximately 300 R. P. M., say, or racing at 3000 R. P. M.
- With the stand-pipe 22 in the pump chamber 10, moreover, an adequate delivery of fuel at even the slowest speeds (as in cranking by hand) is safely assured by the trapping of fuel in the chamber 10. For while the chamber 10 is substantially filled through the pipe 22 at each suction stroke, yet on the succeeding pressure stroke the fuel below the holes 23 cannot start to return, but tends to pass out through the check-valve 33 the very instant that pressure makes itself felt in the chamber.
- It is further to be remarked that notwithstanding the periodicity of the fuel delivery by the pump, the feeding of fuel to the carbureter 2 is not intermittent, but continuous, owing to the air pressure head or cushion at all times maintained above the fuel in the chamber 11, which causes the fuel to flow to the carbureter in a steady stream so long as the needle valve remains open. And besides equalizing the flow of fuel to the carbureter 2, the elastic cushion afforded the liquid in the delivery connection by this chamber 11 absorbs the momentary peaks of the delivery pressure impulses from the pump, and thus cooperates with the free return of liquid through the supply line 3 in maintaining a substantially constant and limited delivery pressure,—well below any value that might overpower the carbureter regulation, force open the needle valve, and flood the carbureter 2 with a supply exceeding the real demand for fuel.
- As regards the elastic fluid cushion through which the pulsator 7 acts on the liquid fuel, it is to be noted that with the supply tank 1 below the pump device 5, as shown, preponderance of vacuum such as would cause fuel to rise excessively high in the pump chamber 10 cannot occur, because the displacement on the pressure stroke of the pulsator 7 cannot exceed that on the suction stroke. On the other hand, preponderance of the pressure stroke arising from leakage of external air into the system at the pulsator 7, or the pipe lines or connections, is always automatically corrected by expulsion of such air from the chamber 10 into the chamber 11 and its ultimate discharge into the air chamber of the carbureter 2, which is open to the atmosphere.
- When a pressure of 2 lbs. is maintained on the surface of the fuel in the chamber 11, as hereinbefore described, the conditions for the feed of fuel are exactly the same as when the standard pressure of 2 lbs. is maintained on the surface of the fuel in the supply tank of a pressure feed system such as heretofore used. For such parity of operating conditions, my system only requires a pressure of 2 lbs. to be raised in a chamber of a few cubic inches capacity, which can be done in a few turns of the engine; whereas the other type of system requires 2 lbs. pressure to be built up in a large fuel tank,—which may be nearly empty at starting. My system is, therefore, much quicker and more efficient in starting than a tank pressure system: indeed, with the parts proportioned, as hereinbefore described, to maintain 2 lbs. pressure in the chamber 11, an ordinary carbureter can be filled in from 5 to 10 seconds.
- Inasmuch as the pulsator 7 is actuated from the cam shaft of the engine at one-half the speed of the crank shaft, the range of variation of the impeller speed is from about 15 strokes per minute during cranking by hand to about 1500 for full speed of the engine,—or in the ratio of 1 to 100. Assuming a car travelling 10 miles per gallon of fuel consumed, its requirement would be 6 gallons per hour for steady operation at a speed of 60 miles per hour, and almost twice this during rapid acceleration,—as when the throttle is suddenly opened at a speed of 5 miles per hour and held open until maximum speed is reached,—since under this condition the charge is taken into the engine at atmospheric pressure, and the load is a maximum. Assuming that the motor needs 10 gal. per hour at the 3000 R. P. M. speed, its requirement at 300 R. P. M., as in idling would apparently be just $\frac{1}{10}$ as much, or 1 gal. per hour. However, the motor is unloaded in idling, and only takes in about $\frac{1}{3}$ of its piston displacement (owing to the 20 in. vacuum then existing in the intake manifold) at each intake stroke; hence it would actually use only $\frac{1}{3}$ gal. in idling.
- Besides the extreme range of the variations of speed and of the fuel requirements indicated above, there is the extreme abruptness of the variation in fuel demand represented by instant opening of the throttle of an idling engine. In other words, the fuel supply needs to be increased thirty-fold on the instant; yet the pressure under which it is fed must remain approximately the same. These extreme requirements I am enabled to meet by virtue of the unchecked return of excess fuel permitted by the absence of the usual valves or the like from the supply line. This, as already mentioned, allows a pulsator 7 of sufficient displacement to feed the requisite quantity in excess of any possible requirements to be employed, yet obviates excessive fuel supply at any time and prevents substantial variation of pressure under even the most extreme variations in operating conditions,—as between high

speed, when the carburetor needle valve is open most of the time, and idling, when the needle valve is closed most of the time.

Having thus described my invention, I claim:

1. A method of feeding liquid fuel under pressure, in amounts adapted to varying demand, in a conduit unchecked as against return of excess fuel, but with check-valved delivery; which method comprises exerting sufficiently rapid alternations of suction and pressure on the liquid in said conduit to surge the same inward under the suction impulses with sufficient energy to enable delivery to be made under the pressure impulses, by virtue of the inertia of the incoming fuel, as required by the demand, even with the conduit substantially open at the supply side of the check-valve means; and permitting fuel in excess of the requirements that is drawn inward by the suction to return through the conduit under the pressure.
2. A method of feeding liquid fuel under pressure, in amounts adapted to varying demand, in a conduit unchecked as against return of excess fuel, but with check-valved delivery; which method comprises exerting sufficiently rapid alternations of suction and pressure on the liquid in said conduit to surge the same inward under the suction impulses with sufficient energy to enable delivery to be made under the pressure impulses, by virtue of the energy of the incoming fuel, as required by the demand, even with the conduit substantially open at the supply side of the check-valve means; permitting fuel in the excess of the requirements that is drawn inward by the suction to return through the conduit under the pressure, and at each passage of fuel through the check-valve means also trapping fuel at the supply side thereof against return as aforesaid.
3. A method of feeding liquid fuel under pressure through a check-valved feed conduit to a carburetor with regulated admission, in amounts adapted to varying demand; which method comprises exerting sufficiently rapid alternations of suction and pressure on the liquid at the supply side of the check-valve means, through an elastic fluid cushion, to surge the fuel inward in the conduit under the suction impulses with sufficient energy to enable delivery to be made, by virtue of the inertia of the incoming fuel, when permitted by the carburetor regulation, even with said conduit substantially open toward the supply; and elastically cushioning the liquid in the delivery connection to the carburetor and thereby safe-guarding the latter against flooding by the pressure impulses.
4. The processes of conveying liquid fuel from a source of supply to a point of use through a system comprising a chamber

with an inlet unchecked as against return of excess fuel and a check-valved outlet for the fuel, but substantially closed from the atmosphere, and containing a confined body of gas; which method comprises producing such rapid alterations of rarefaction and compression of said gas as to draw charges of the liquid into said chamber and exert pressure on said charges with sufficient frequency for the inertia of the inflowing liquid to enable the pressure to force portions of the charges through said outlet to the point of use, even with the inlet substantially open; and permitting the remainder of the charges to return through the inlet.

5. A method of feeding liquid fuel under pressure to a motor vehicle engine, in amounts adapted to varying demand, through a system comprising a check-valved feed conduit with a confined body of elastic fluid maintained in contact with the liquid fuel at the supply side of the check-valve means; which method comprises exerting alternations of suction and pressure on the elastic fluid, with a frequency proportional to the speed of the engine, and thereby surging the fuel inward in said conduit with corresponding frequency, so that the varying inertia of fuel in the supply end of the conduit for varying frequencies of alternation enables fuel which is drawn inward by the suction to be passed through the check-valve means under the pressure, as required by the varying demand, even with the conduit substantially open at the supply side of the check-valve means; and permitting fuel in excess of the requirements that is drawn inward as aforesaid to return through the conduit under the pressure.

6. A system of the character described for feeding liquid fuel under pressure, self-adapting to varying demand; said system comprising a substantially closed check-valved feed conduit, with a confined body of elastic fluid in contact with the liquid fuel therein at the supply side of the check-valve means, and means for exerting alternate suction and pressure on the elastic fluid and thereby surging fuel in the conduit; said conduit remaining open at the supply side of its check valve means to permit surging back and forth therein during periods of low demand, and the inertia of the fuel in the supply end of the conduit enabling delivery to be made through said check-valve means under the pressure impulses, even with the conduit open.

7. A system for feeding liquid fuel under pressure, substantially closed from fuel supply to fuel delivery, and self-adapting, as hereinafter described, to variations in the demand for fuel; said system comprising a pump with means of producing alternate suction and compression; a check-valved delivery from said pump; a fuel supply

conduit to said pump permitting return, under the pressure stroke of the pump during periods of low fuel demand, of fuel in excess of the demand that has been drawn 5 into the pump by the suction; and means for trapping in the pump a portion of the fuel drawn in as aforesaid, to prevent its return; the inertia of fuel in the supply conduit enabling the pump to deliver under pressure 10 without closure of said conduit, and the return of fuel as aforesaid preventing excessive pressure when the demand falls below the potential pump capacity.

8. A fuel pump comprising a pumping 15 chamber containing gas, means for causing alternate compression and rarefaction of said gas, an outlet passage from said chamber having therein a check-valve, means to restrict the outflow through said valve at 20 times to less than the maximum capacity of the pump, and an inlet conduit connecting said chamber to a source of supply, said conduit being open to permit the liquid entering said chamber in excess of the permitted 25 outflow to surge back through the said conduit under the influence of the compression of the gas, the discharge check-valve being constructed and arranged to open under the compression stroke by reason 30 of the inertia of the inflowing liquid, without closure of the inlet conduit.

9. A system for feeding liquid fuel under pressure to a motor vehicle engine, self-adapting, as hereinafter described, to variations 35 in the demand for fuel, and comprising a pump with an elastic fluid pulsator, driven by the engine for producing alternate suction and compression, a check-valved delivery from said pump, and a fuel supply 40 conduit to said pump permitting return, under the pressure stroke of the pump during periods of low demand, of fuel in excess of the demand that has been drawn 45 into the pump by the suction; the inertia of fuel in the supply conduit enabling the pump to deliver under pressure without closure 50 of said conduit, and the return of fuel as aforesaid preventing excessive pressure when the demand falls below the potential pump capacity.

10. A fuel supply system of the character described comprising a carbureter and its fuel admission valve, a pumping chamber with delivery connection to said carbureter, 55 an elastic fluid pulsator for producing alternations of suction and compression in said chamber, and a fuel conduit from the source of supply to said pump chamber which is open during normal functioning of the device 60 to permit back flow of liquid whenever the resistance to outflow through the delivery connection into the carbureter exceeds the operating resistance to such back flow.

65 11. A pressure-feeding fuel supply system

comprising, in combination with a carbureter and its fuel admission valve, a conduit leading to the carbureter from the supply unchecked as against return of excess fuel, but with check-valved delivery to the carbureter; and an elastic fluid pulsator for exerting sufficiently rapid alternations of suction and pressure on the liquid to surge it inward under the suction impulses with sufficient energy to enable delivery to be 70 made under the pressure impulses, when permitted by the carbureter valve regulation, even with said conduit substantially open toward the supply.

12. A pressure-feeding liquid fuel supply 80 system comprising, in combination with a carbureter and its fuel admission valve, a conduit leading to the carbureter from the supply unchecked as against return of excess fuel; an elastic fluid pulsator for exerting sufficiently rapid alternations of suction and pressure on the liquid to surge it inward under the suction impulses with sufficient energy to enable delivery to be 85 made under the pressure impulses, when permitted by the carbureter valve regulation, even with said conduit substantially open toward the supply; and a check-valve in the delivery connection of said conduit to the carbureter adapted to remain closed under 90 the back-pressure maintained by the carbureter valve when closed, and to pass the fluid to the carbureter under the pulsator impulses when the carbureter valve is open.

13. A pressure-feeding liquid fuel supply 100 system comprising, in combination with a carbureter and its fuel admission valve, a conduit leading to the carbureter from the supply unchecked as against return of excess fuel; an elastic fluid pulsator for exerting sufficiently rapid alternations of suction and pressure on the liquid to surge it inward under the suction impulses with sufficient energy to enable delivery to be 105 made under the pressure impulses, when permitted by the carbureter valve regulation, even with said conduit substantially open toward the supply; and a check-valve in the delivery connection of said conduit to the carbureter, with means affording an elastic 110 cushion for the liquid in said connection and thereby safeguarding the carbureter against flooding by the pressure impulses.

14. A pressure-feeding fuel supply system 120 comprising, in combination with a carbureter and its fuel admission valve, a pump with a motor-driven elastic fluid pulsator for producing alternate suction and compression and a fuel supply connection unchecked as against return of excess fuel, and a delivery connection to the carbureter with a pressure chamber and a check-valve; so that on the pressure strokes fuel may flow 125 from the pump toward the supply as well as toward the carbureter, and flooding of the 130

latter by the pressure impulses may be prevented.

15. A system of the character described for feeding liquid fuel under pressure in a substantially continuous flow, self-adapting, as hereinafter described, to variations in the demand; said system comprising a substantially closed check-valved feed conduit with an elastic fluid cushion at the supply side 10 of its check-valve means, a pressure chamber beyond said check-valve means, and means beyond said pressure chamber for controlling the delivery from said conduit according to demand, so that back-pressure may be imposed on the fuel; and means for producing sufficiently rapid alternations of suction and pressure impulses on the fuel at the supply side of said check-valve means through said cushion to surge the fuel inward in said conduit with such energy that the inertia of the fuel in the supply end of the conduit enables delivery to be made through said check-valve means, even with the conduit substantially open at the supply 20 side of said check-valve means, whenever flow from said chamber under the demand has reduced the pressure therein below that due to the pressure impulses.

16. A fuel supply system for a motor ve-

hicle engine comprising a carburetor with means for controlling the admission of fuel thereto according to the demand, so that back pressure may be imposed on the fuel; a pump with an elastic fluid pulsator for producing alternate suction and pressure impulses, in frequency proportional to the speed of the engine; a check-valved delivery connection from said pump to said carburetor, provided with a pressure chamber beyond its check-valve means; and a fuel supply conduit to said pump permitting return therethrough, under the pressure stroke of the pump during periods of low fuel demand, of fuel in excess of the demand that has been drawn into the pump by the suction; the inertia of the fuel in the conduit enabling delivery to be made through said check-valve means under the pressure impulses, even with the supply conduit open, whenever flow from said chamber under the demand has reduced the pressure in said chamber below that due to said pressure impulses.

In testimony whereof, I have hereunto signed my name at Philadelphia, Pennsylvania, this 29th day of September, 1921.

JOSEPH PERCY REMINGTON.
